TOILET SEAT

Francis J. Moore, Minneapolis, Minn.

Application August 13, 1936, Serial No. 95,800

8 Claims. (Cl. 4—240)

My present invention provides an extremely simple and highly efficient divided toilet seat of the adjustable type and, generally stated, the invention consists of the novel devices, combinations of devices and arrangement of parts hereinafter described and defined in the claims.

The purposes and objects of a seat of this character are well understood, but, briefly stated, are to provide a seat suitable for adults and children.

10 Also the invention provides such a seat that is of neat appearance, strong, durable and capable of very quick and easily performed adjustments.

In the accompanying drawing, which illustrates the invention, like characters indicate like parts 15 throughout the several views.

Referring to the drawing:

Fig. 1 is a plan view showing the improved seat, an expanded position thereof being shown by full lines and a contracted position thereof being indicated by dotted lines;

20 Fig. 2 is a fragmentary view with some parts in horizontal section;

Fig. 3 is a fragmentary edge elevation of the seat, some parts being removed;

25 Fig. 4 is a section taken on the line 4—4 of Fig. 1;

Fig. 5 is a fragmentary view in bottom plan view showing parts in the vicinity of the section line 4—4;

30 Fig. 6 is a fragmentary view corresponding to Fig. 2 but illustrating a slightly modified construction; and

Fig. 7 is a section taken on the line 7—7 of Fig. 6.

35 Referring first to the construction illustrated in Figs. 1 to 5, inclusive, the numeral 8 indicates the two seat sections; and the numeral 9 indicates an anchoring bracket which is adapted to be rigidly secured to the body of the bowl by any 40 suitable means, such as depending studs 10 that may be embedded in the bowl. The bracket 9 is provided with a rounded lug 11 through which a transversely extended hinge-rod 12 is extended and to which said rod is rigidly secured by suitable means, such as a pin 13.

45 The sections of the seat are independently pivoted on the projecting ends of the hinge-rod 12. The seat sections are adapted to be made of any suitable material, such as wood, plain or 50 coated with rubber, or of composition material. Especially for the application of wooden sections metal sleeves 14, which act as bushings, are rigidly secured to the rear ends of the seat sections and mounted on the hinge-rod for both sliding and pivotal movements. Preferably, and

as shown, the exteriors of these sleeves or bushings 14 are rectangular in cross-section and are set into grooves or rabbeted seats formed in the ends of said seat sections. As best shown in Fig. 2, the sleeves 14 are secured to the seat sections 5 by screws 15 that are countersunk into the inner walls of said sleeves and are screwed into the seat sections. To permit of the application of the screws, the outer walls of the sleeves are provided with large openings 16 into one of which is 10 screwed a cap screw or plug 17. In each cap nut or plug 17 is mounted a spring-pressed latch ball 18 that is engageable with a groove 19 formed in the corresponding end of the hinge-rod.

15 Cap screws 20 are screwed into the ends of the hinge-rod 12 and limit the lateral outward movements of the seat sections, in which position the spring-pressed latch balls engage the grooves 19 and tend to hold the seat sections under maximum separated or seat-expanded positions. A reasonable amount of force applied to the seat 20 sections will, however, overcome the spring-pressed balls 18 and move the seat sections inward on the hinge-rod. Here it will be noted that the sleeves or bushings 14 terminate short of the inner edges of the rear portions of the seat sections so as to clear the lug 11 and permit the seat sections to be moved together, as shown by dotted lines in Fig. 1, thereby adjusting the seat 25 to its smallest size.

30 Resilient bumpers or stop elements 21, preferably of rubber, are cemented or otherwise rigidly secured to approximately L-shaped metal anchoring clips 22 which, in turn, are secured to the seat sections with freedom for transverse adjustments by screws 23 that work through slots 24 in 35 said metal clips and are screwed into the seat sections. By lateral adjustments of the clips 22, the rubber or other pliable bodies 21 can be adjusted so that their tops and depending portions closely engage with the bowl rim when the seat sections 40 are expanded to their maximum positions.

45 The slightly modified structure illustrated in Figs. 6 and 7 is especially intended for use when the seat sections are made of moulded material covered with rubber or the like. In these two views the seat sections are indicated by the character 8a, the hinge-rod by the character 12a, the bushing by the character 14a, the cap nut by the character 17a, the spring-pressed ball by the character 18a, and the co-operating groove by the character 19a. The sleeve or bushing 14a, in 50 this instance, is a cylinder and is driven into and closely fits seat formed in the seat section.

55 It is important to note that the seat sections are capable of independent lateral as well as in-

dependent pivotal movements so the seat can be drifted from one side to the other and the sections can be independently raised. Also, it will be noted that the projecting plugs 17 have outstanding heads that will afford knobs or finger pieces that may be engaged to laterally adjust the seat sections without taking hold of the seat sections proper. Suitable knobs for the above purpose may be applied to the sections at the 10 sides, top or where desired.

From the foregoing the structure, the purposes and advantages thereof are thought to have been made obvious. It will be understood that the structure illustrated is capable of modification within the scope of the invention herein disclosed and claimed.

What I claim is:

1. A toilet seat comprising an anchoring bracket, a hinge-rod rigidly secured to and projecting 20 transversely in opposite directions therefrom, seat sections having grooved ends, sleeves seated in said grooves and rigidly secured to the respective seat sections, said sleeves being telescoped onto the ends of said hinge-rod for pivotal and 25 sliding movements thereon.

2. The structure defined in claim 1 in which said anchoring bracket has a collar-like hub through which said hinge-rod is directly passed, said sleeves being terminated short of the inner 30 rear portions of said seat sections so as to clear the hub of said anchor bracket and permit the seat sections to be moved into close association.

3. In a toilet seat, an anchoring bracket, a hinge-rod applied to and projecting therefrom 35 transversely in opposite directions, and seat sections applied to said rod and thereby supported for pivotal movements and for lateral adjustments, in further combination with sleeves applied to the rear ends of said seat sections and 40 through which said hinge-rod is extended, said rod, near its ends, having grooves, and spring-pressed latch elements carried by the seat sections and engageable with said grooves.

4. In a toilet seat, an anchoring bracket, a hinge-rod applied to and projecting therefrom transversely in opposite directions, and seat sections applied to said rod and thereby supported for pivotal movements and for lateral adjustments, in combination with bearing sleeves applied to the rear ends of said seat sections and through which said hinge-rod is extended, detachable plugs applied through said sleeves, spring-pressed balls mounted in said plugs, said 10 hinge-rod having grooves with which the said spring-pressed balls engage.

5. In a toilet seat, an anchoring bracket, a hinge-rod applied to and projecting therefrom transversely in opposite directions, and seat sections applied to said rod and thereby supported for pivotal movements and for lateral adjustments, in combination with bearing sleeves applied to the rear ends of said seat sections and through which said hinge-rod is extended, detachable plugs applied through said sleeves, spring-pressed latch elements mounted in said plugs, said hinge-rod having grooves with which the said spring-pressed balls engage, and said rod, 20 at its ends, having cap screws, the heads of which 25 project and afford stops for limiting the separating movements of said seat sections.

6. In a toilet seat, a fixed anchoring bracket, a hinge-rod rigidly secured to said anchoring bracket and projecting therefrom transversely 30 in opposite directions, and seat sections mounted for free and independent pivotal and free and independent sliding movements on the ends of said rod.

7. The structure defined in claim 6 in which 35 said rod, at its ends, has detachable stops limiting the separating movements of said seat sections.

8. The structure defined in claim 6 in which the seat sections are provided with independent bearing sleeves applied at their rear portions and 40 which are directly mounted on the projecting ends of said rod.

FRANCIS J. MOORE.
